UNITED STATES PATENT OFFICE.

HARLAN S. GANO, OF PITTSBURGH, PENNSYLVANIA, ASSIGNOR TO WESTINGHOUSE ELECTRIC AND MANUFACTURING COMPANY, A CORPORATION OF PENNSYLVANIA.

TEMPERATURE REGULATOR.

Application filed October 23, 1925. Serial No. 64,363.

My invention relates to control systems, and particularly to temperature control systems for heated devices.

One object of my invention is to provide a relatively simple and efficient temperature control system for a heated device.

Another object of my invention is to provide a temperature control system that shall embody means for preventing hunting of the system.

Another object of my invention is to provide a temperature control system that shall embody means for varying the energization of the heating means in a series of increments of decreasing lengths of time as the desired temperature is approached.

In practicing my invention, I provide an electro-responsive device for selectively energizing an energy-controlling means, a main thermocouple, subjected to the temperature of the device being heated, for actuating the electro-responsive device, and a plurality of opposed auxiliary thermocouples connected in series circuit relation with the main thermocouple and selectively energized in accordance with the operation of the electro-responsive device.

In the single sheet of drawings,

Figure 1 is a diagram of connections of a system embodying my invention, and

Fig. 2 is a view, partially in side elevation and partially in section, of a different form of energy-controlling means.

Referring more particularly to the control system illustrated in Fig. 1 of the drawings, I have there shown generally a heated device 11 that may, for purposes of illustration, be considered as a furnace that is heated by an electric heating element 12. Both the furnace structure 11 and the heating means 12 may be of any suitable or desired type, and as they form no part of the present invention, are not illustrated or described in detail.

Energization of the heating element 12 is effected by a transformer 13 having a primary winding 14 and a secondary winding 15, the latter being provided with a plurality of taps that are connected to stationary contact terminal members, any desired number of which may be provided in accordance with the general operation of the entire system. I have illustrated seven contact terminal members designated by the numeral 16.

A movable contact arm 17 is provided, that is pivotally mounted at one of its ends, and

that may be actuated by a motor armature 18, a suitable mechanical connection therebetween being effected by a shaft 19. More or less of the secondary winding will be in circuit with the electrical resistor member 12 in accordance with the angular position of the arm 17 and its engagement with the spaced terminal members 16.

The field winding 21 is connected to a suitable source of supply of electric energy (not shown) and a motor armature 18 is selectively energized, in a manner to be herein-after described more in detail, in order to effect an operation of the motor armature in either a forward or in a reverse direction.

Means for controlling the energization of the heating element 12 comprises an electro-responsive device 22 that is energized by a main thermocouple 23 that is preferably located within the furnace structure to be subjected to the temperature of the heated device. The thermocouple 23 comprises a pair of wires of dissimilar metals as usually employed in the art for such purposes. While I do not desire to be limited thereto, I may use a couple comprising one wire made of so-called advance metal which is an alloy of copper and nickel, and another of copper, which is adapted to relatively low temperatures only. The outer end of the advance wire is connected through a conductor 24 to one terminal 25 of the electro-responsive device 22 which comprises a moving coil 26, a permanent field magnet 27 and a movable pointer and contact arm 28 operatively secured to the moving coil 26. The other end of the coil 26 is connected to a terminal member 29 which is connected by a conductor 31 to the outer terminal of the copper element of an auxiliary thermocouple 32 made of the same metals as the thermocouple 23. The outer end of the advance metal element of the thermocouple 32 is connected to the outer terminal of the advance metal element of a second auxiliary thermocouple 33 identical in construction with the thermocouple 32.

The outer terminal of the copper element of the thermocouple 33 is connected through a conductor 34 to the outer terminal of the same metal element in the thermocouple element 23. The two auxiliary thermocouples 32 and 33 are located within a suitable casing 35 that is preferably made of a heat insulating material and that may be located anywhere relatively to the furnace structure,

and I prefer to locate it relatively close to the electro-responsive element 22.

It is necessary, when using a thermocouple, to insure a substantially constant temperature for the cold junction in order that the reading or indication of the electro-responsive device energized and controlled by the thermocouple shall be substantially constant. The hereinbefore described connections between the main and the plurality of auxiliary thermocouples, which latter are connected in opposed relation relatively to each other as to the electromotive force generated therein, permit of employing the three thermocouples while using only a single cold junction, which latter may be located within a casing 36 that is preferably located relatively close to the electro-responsive device 22.

Within the casing 36 there are mounted a heating element 37 and a thermostatic member 38 that are energized from a suitable source of supply of electric energy (not shown), the adjustment of the thermostatic element 38 being such that the temperature of the ends of the conductor 31, which is made of copper, and of the conductor 24 that is made of advance metal, shall be maintained at a substantially constant value, in a manner well known in the art.

The indicator arm 28 is adapted to selectively engage contact members 39 and 41 which may be adjustably mounted within a casing 42 of the electro-responsive device 22, the contact members 39 and 41 being connected to suitable terminal members on the outside of the casing 42.

A plurality of contactors 43 and 44 constitute a part of the system and severally comprise a pair of upper co-operating contact members 45, a pair of lower co-operating contact members 46 and a pair of operating and holding coils 47. Auxiliary co-operating contact members 48 are provided on each of the contactors which open and close simultaneously with the upper contact members 45. The construction of the respective contactors is such that either one or the other of the two co-operating contact members 45 and 46 are in engagement in accordance with the energization of the actuating coils 47.

The contact member 39 is electrically connected by a conductor 49 to one terminal of the actuating coil 47 of the contact member 45, the other end thereof being connected through conductors 51 and 52 to one conductor of a suitable supply circuit 53 that is here indicated as of negative polarity. The contact member 41 is connected by a conductor 54 to one terminal of the actuating coil of the contactor 44, the other end thereof being connected by a conductor 55 to the conductor 52.

A supply circuit conductor 56, that is designated as of positive polarity, is connected to a terminal member 57 mounted on the cas-

ing 42, which is, in turn, connected to the movable contact arm 28. The member 57 is also connected to a conductor 58 that is connected to the stationary contact member of the two co-operating members 45 of the two contactors. The fixed contact member of the lower sets of co-operating members of the two contactors 43 and 44 are connected together by a conductor 59 and are also connected to the conductors 52 and 55.

Means for selectively heating and energizing the auxiliary thermocouples 32 and 33 comprise a heating coil 61 that is so located within the casing 35 as to effect heating of the thermocouple 32, when energized, and a heating coil 62 that is so located within the casing 35 as to effect heating of the thermocouple 33, when energized. One terminal of each of the heating coils 61 and 62 is connected by a conductor 63 to the conductor 58. The other terminal of the coil 61 is connected through a conductor 64 to one contact member of the auxiliary contacts 48 of the contactor 43, the other contact member being connected through a conductor 65 to the conductor 52. The other end of the heating element 62 is connected through a conductor 66 to one contact member of the auxiliary set of contacts of the contactor 44, the other terminal thereof being also connected to the conductor 65 and, therefore, to the conductor 52.

The system illustrated more particularly in Fig. 1 of the drawings is shown as applied to an electric heating element, but the system embodying my invention is not limited thereto and may be applied to the control of a gaseous or of a liquid fuel. A furnace structure 67 is illustrated schematically, and in a fragment only, in Fig. 2 of the drawings, the fuel entering the furnace structure 67 through a conduit 68 that has an adjustable valve 69 connected therewith. A conduit 71 is connected to the other end of the valve 69 and is suitably connected to a fuel reservoir.

The valve 69 is provided with a screw-threaded stem 72, a gear wheel 73 being mounted thereon and operable to cause movement of the stem 72 in such manner as to vary the amount of fuel that flows through the valve 69. A pinion 74 is mounted on an actuating shaft 75, which shaft may be the same as that mechanically connected to the shaft 19 of the motor armature 18, as shown in Fig. 1 of the drawings.

The operation of the system embodying my invention is substantially as follows. If it be assumed that the system is connected to a suitable source of supply and that the heating element 12 is being heated, and that the material being heated in the furnace structure 11, or in the furnace structure 67, is still at a temperature much below a predetermined temperature, it is obvious that the electro responsive device 22, and particularly the

movable coil 26, is energized at such a value that the contact-making member 28 is in engagement with the contact member 39. This is obvious from the fact that the contact-making arm 28 is to be located intermediate between the members 39 and 41 when the temperature of the thermocouple 23 is that which it is desired to maintain within the furnace structure, and which is therefore that to which any material located within the furnace structure is to be raised to, or maintained at.

The engagement of the arm 28 with the contact member 39 effects the closing of an electric circuit from conductor 56 through terminal 57, arm 28, contact member 39, conductor 49, coil 47 of the contactor 43, conductor 52, and from there to the other supply circuit conductor 53. This effects the actuation of the contactor 43, causing the upper contact members 45 and the auxiliary contact members thereof to engage, and also causing the simultaneous disengagement of the co-operating contact members 46 of that contactor. This effects the closing of an energizing circuit extending from supply circuit conductor 56 through conductor 58, co-operating contact members 45 of the contactor 43, conductor 76, armature 18, conductor 77, the lower set of contact members 46 of the contactor 44 and conductor 52 to the other side of the supply circuit 53. The motor armature is actuated in a predetermined direction such that the arm 17 is moved to engage the one or the other of the terminal members 16 connected to taps on the transformer that will include a greater portion of the secondary winding 15 in the energizing circuit of the heating element 12.

An auxiliary heating circuit is simultaneously established by and through the auxiliary contacts 48 of the contactor 43 that is traced as follows: from supply circuit conductor 56 through a portion of the conductor 58, conductor 63, through the heating element 61, conductor 64, co-operating contacts 48 of the contactor 43, conductor 65, conductor 52, and from there to the other supply circuit conductor 53. This latter circuit causes heat to be generated in the coil 61, thereby energizing the auxiliary thermocouple 32 which generates an auxiliary electromotive force which is additive to that of the main thermocouple 23.

The effect of this auxiliary thermal electromotive force is to cause a greater current to traverse the circuit including the plurality of thermocouples and the moving coil 26, whereby disengagement between the moving arm 28 and the contact member 39 is effected sooner than would otherwise be the case if the auxiliary thermocouple were not present. This means that, if the adjustment within the electro-responsive device 22 is such that it will occupy its neutral or intermediate posi-

tion, substantially as shown in Fig. 1 of the drawings, at a predetermined temperature of the thermocouple 23, it will be caused to be disengaged from the contact member 39 in advance of the time when the main thermocouple 23 will have reached that predetermined temperature because of the energization of the auxiliary thermocouple.

By such disengagement, the hereinbefore described energizing circuit will be interrupted, and the contactor 43 will be returned to the other of its limiting positions, which is substantially that shown in Fig. 1 of the drawings.

As was hereinbefore stated, disengagement of the arm 28 and the contact member 39 is effected in advance of the time that the thermocouple 23 has reached a predetermined temperature, and the material being heated within the structure 11 is, therefore, still below such predetermined temperature. Upon such disengagement and the simultaneous de-energization of the circuits hereinbefore described, the thermo-couple 32 is also de-energized and its thermal electromotive force is decreased, the time of such decrease being in accordance with well-known laws as to heat storage and heat radiation.

When this electromotive force has been reduced to such an amount that the total thermal electromotive force in the circuit comprising the main and the auxiliary thermocouples and the coil 26, is reduced to such a value that the arm 28 will again be moved to the left and re-engage the contact member 39, it will operate to again establish the hereinbefore described energizing circuits to cause the energization of the heating element 12 in the furnace structure 11, and of the auxiliary heating coil 61.

As the temperature of the main thermocouple 23 is now relatively higher than it was at the beginning of the previous time of energization, the sum of the thermal electromotive forces in the main and the auxiliary thermocouple circuit, will increase more rapidly, and disengagement of the arm 28 and of the contact member 39 will be effected in a shorter time than the previous time of energization. In other words, the variation of the energization of the main heating element 12 is effected in a series of increments of decreasing durations or lengths of time as a predetermined temperature is approached. This method or cycle of operations has the effect of preventing overshooting, or, as it is usually termed, hunting of the system, which hunting is usually present in case no auxiliary means is provided to prevent the same. Such hunting is ordinarily caused by the thermal time lag between the heat generated and its effect upon the controlling devices.

If, for any reason, the temperature within the furnace structure 11 and, therefore, of

the main thermocouple 23, should exceed a predetermined value, the contact arm 28 will be caused to engage the contact member 41 by reason of the relatively high thermal electromotive force within the circuit comprising the main and the auxiliary thermocouples and the coil 26. This will effect the actuation of the contactor 44, whereby current will be caused to traverse the armature 21 in a direction opposite to that in which it is caused to flow when contactor 43 is engaged, and the arm 17 will be caused to engage one or the other of the contact terminal members connected to taps in the primary winding that 15 include a smaller number of turns thereof, thereby reducing the supply of energy of the heating element 12.

Simultaneously with this connection, the auxiliary heating coil 62 is energized, which 20 effects energization or the heating of the auxiliary thermocouple 33 that is connected in opposed relation relatively to the thermocouple 32, whereby a thermal electromotive force of the opposite polarity is generated, 25 thereby reducing the thermal electromotive force within this circuit and causing disengagement of the arm 28 of the contact member 41 in advance of the time that the thermocouple 23 reaches a predetermined temperature.

The combination of the auxiliary heating coils and the auxiliary oppositely-connected thermocouples is such that it will compensate for the thermal lag inherent in such 30 control devices, and, by a proper proportioning thereof, it is possible to obtain very close regulation of temperature or its maintenance at or near a predetermined value, and to effect a variation of the energization of a heating means in a series of increments of 35 decreasing lengths of time as the predetermined temperature is approached.

The operation of the cold junction assembly, as hereinbefore described, is that usual in the art and its operation need not, therefore, be described in detail.

The operation of the system when applied to a gaseous or fluid fuel, of the type illustrated generally in Fig. 2 of the drawings, 40 is substantially the same and need not be further described in detail.

While I have illustrated and described the system embodying my invention as applied to the heating of heated devices, it is not limited thereto, as it may also be applied to various other systems or installations in which heat interchange is to be effected and in which the temperature of an appliance, a device or a medium is to be maintained substantially constant. Hence, I may apply it to the regulation of the temperature of feed water in a power plant, in which case the furnace structure 11, shown in Fig. 1 of the drawings, will be replaced by the structure 45 of a feed water heater and the thermocouple

23 will be thermally associated therewith. The motor comprising the armature 18 and the field winding 21 will be operatively associated with means for regulating the amount of fluid or steam entering the feed 70 water heater.

Various modifications and changes may be made without departing from the spirit and scope of the invention, and I desire, therefore, that only such limitations shall be 75 placed thereon as are imposed by the prior art.

I claim as my invention:

1. A temperature control system comprising a contact-making member, an actuating coil therefor, a main thermocouple, subjected to the temperature to be controlled, for energizing said actuating coil, and an auxiliary thermocouple, energized in accordance with the position of said contact-making member, for preventing hunting of said system.

2. In a control system, the combination with a thermocouple subjected to the temperature of a device to be controlled, means for varying the operation of the device to be controlled, an electro-responsive device connected to the thermocouple and adapted to control the means for varying the operation of the device to be controlled, of a second thermocouple connected in electric circuit 95 with the first named thermocouple and energized in accordance with the operation of said electro-responsive device for preventing hunting thereof.

3. In a control system, the combination 100 with a thermocouple subjected to the temperature of a device to be controlled, means for varying the operation of the device to be controlled, an electro-responsive device connected to the thermocouple and adapted to control the means for varying the operation of the device to be controlled, of a plurality of auxiliary thermocouples connected in electric series circuit relation to the first-named thermocouple and selectively energized in accordance with the operation of said electro-responsive device for preventing hunting.

4. In a control system, the combination 110 with a thermocouple subjected to the temperature of a device to be controlled, means for varying the operation of the device to be controlled, an electro-responsive device connected to the thermocouple and adapted to control the means for varying the operation of the device to be controlled, of a plurality of opposing auxiliary thermocouples connected in electric series circuit relation to the first-named thermocouple and selectively energized in accordance with the operation of 115 said electro-responsive device for preventing hunting.

5. In a control system, the combination 120 with a thermocouple subjected to the temperature of a device to be controlled, means for varying the operation of the device to be con-

- trolled, an electro-responsive device connected to the thermocouple and adapted to control the means for varying the operation of the device to be controlled, of a plurality of thermocouples connected in series circuit relation with the first-named thermocouple, and means for effecting selective energization thereof in accordance with the operation of the electro-responsive device to prevent hunting thereof.
- 5 6. In a control system, the combination with an electro-responsive device for controlling the energization of a heating means, of a plurality of thermocouples connected in series-circuit relation with each other and with the electro-responsive device, and a single cold junction for all of said thermocouples.
- 10 7. In a control system, the combination with an electro-responsive device for controlling the energization of a heating means, of a main thermocouple for causing actuation of said electro-responsive device at predetermined temperatures, and auxiliary thermocouples selectively energized in accordance with the operation of said electro-responsive device for causing it to be actuated in advance of the time of reaching said predetermined temperature.
- 15 8. In a control system, the combination with an electro-responsive device for controlling the energization of a heating means, of a main thermocouple for causing actuation of
- 20 of said electro-responsive device at predetermined temperatures, a plurality of opposed auxiliary thermocouples connected in series-circuit relation with said main thermocouple, and heating means for selectively energizing said auxiliary thermocouples in accordance with the operation of said electro-responsive device for causing it to be actuated in advance of said predetermined temperature.
- 25 9. The combination with a thermo-couple, and electro-responsive means actuated thereby, of heating means disposed out of thermal relation with said thermo-couple, and a second thermo-couple energized by said heating means for causing said electro-responsive means to be actuated in advance of a temperature at which the first thermo-couple, when acting alone, would be effective to actuate it.
- 30 10. The combination with an electro-responsive device operable to a plurality of positions, and a thermo-couple for actuating said device from one position to another in response to predetermined temperatures of said thermo-couple, of heating means, and a second thermo-couple energized thereby for causing said electro-responsive device to be actuated from one position to another in advance of the temperature at which said first thermo-couple, when acting alone, is effective to actuate it.

In testimony whereof, I have hereunto subscribed my name this 8th day of October, 1925.

HARLAN S. GANO.
